Paint holder for paint buckets and similar containers and equipment used by painters, comprising a hook having a U-shaped member with leg portions disposed at opposite sides of a ladder rail, and a tray having side walls and a bottom, the tray being supported by the hook, the tray being adapted to receive a paint bucket.

UNITED STATES PATENT OFFICE

2,444,986

HOLDER FOR PAINT BUCKETS AND THE LIKE

William Charles Gebhardt, San Antonio, Tex.

Application August 10, 1945, Serial No. 610,103

4 Claims. (Cl. 248—210)

1

The present invention relates to new and useful improvements in holders for paint buckets and similar containers and equipment used by painters and has for its primary object to provide a device of this character adapted for attaching to a ladder for the purpose of holding the bucket and other painter's equipment in a convenient position while standing on the ladder.

An important object of the invention is to provide an attachment of this character, which can be readily applied to a ladder and removed therefrom and which can be easily taken apart for convenience and carrying in a compact form.

A still further object of the invention is to provide an attachment of this character by means of which the several parts may be assembled in a reverse position so that the paint bucket may be held at either side of the ladder.

Another object of the invention is to provide a device of this character of simple and practical construction, which is strong and durable, efficient and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary front elevational view of a ladder showing the paint holder in position thereon.

Figure 2 is a vertical sectional view taken substantially on a line 2—2 of Figure 1.

Figure 3 is a transverse sectional view taken substantially on a line 3—3 of Figure 2.

Figure 4 is a fragmentary front elevational view showing the device arranged on an opposite side of the ladder, and

Figure 5 is a fragmentary sectional view taken substantially on a line 5—5 of Figure 3.

Referring now to the drawings in detail, wherein for the purpose of illustration I have disclosed a preferred embodiment of the invention, the numeral 5 designates a hook constructed of strap metal and adapted for engaging a rung 6 of a ladder and with the lower portion of the hook twisted to extend flatly along the inside of a rail 7 of the ladder.

A U-shaped member 8 has its leg portions 9 disposed at opposite sides of the rail 7 and with the bight portion 10 of the U-shaped member positioned transversely across the front of the rail.

2

The leg portions 9 of the U-shaped member are formed with openings 11 adapted to receive bolts 12 and 13.

The bolt 12 is inserted through an opening 14 in the lower portion of the hook 5, said lower portion of the hook being positioned against the inside of one of the leg members 9 for securing said U-shaped member to the hook. The lower end of the hook is bent angularly, as indicated at 15, under the leg portion 9 of the U-shaped member, as will be apparent from an inspection of Figure 5 of the drawings.

A tray 16 is formed with upstanding side walls 17 at its sides and one end, the other end of the tray being open, one of the side walls 17 being disposed parallel to the leg portion 9 attached to the hook 5 and is formed with an opening 17a adapted to receive the bolts 12. The lower portion of the side wall 17 of the tray is also formed with a slotted opening 18 adapted to receive the angular lower end 15 of the hook.

The upper edges of the side walls of the tray are also formed with outwardly extending flanges 19 overlying the leg 9 of the U-shaped member 8.

The tray 16 is adapted to hold putty, or similar material, and the inner end of the tray is formed with an opening 20 in the bottom thereof adapted for receiving the blade of a putty knife 21 for supporting the knife in an upright position in the tray.

By attaching the tray to the lower end of the hook 5, the tray will thus be supported on the inside of the rail 7 of the ladder, as will be apparent from an inspection of Figure 1 of the drawings.

To the outside leg 9 of the U-shaped member 8 is secured a vertical bar of strap metal 22 by means of the fastening 13, the bar extending above and below the U-shaped member 8 and is formed at its upper end with a hook 23 adapted for engagement by the bail, or handle, 24 of a paint bucket, or other receptacle, 25.

The lower end of the bar 22 is bent angularly outwardly, as indicated at 26, and positioned in a notch 27 in the lower edge of an arcuate plate 28 secured to the bar 22 by means of a bolt 29. The plate 28 is pivotally supported on the bolt 29 and the notch 27 is of a length greater than the bar 22, as will be apparent from an inspection of Figure 2 of the drawings, whereby to enable the plate 28 to assume a horizontal position and thus to engage the side of the bucket 25 to support the bucket perpendicularly at the outside rail.

The bar 22 is also pivoted on the bolt 13 so that the bar will also gravitate into a perpendicular position.

In Figures 1 to 3 inclusive, I have illustrated the invention mounted for use on the right-hand rail 7 of a ladder, while in Figure 4 the invention is shown mounted on the left-hand rail of the ladder, this being accomplished by attaching the lower end of the hook 5 and bar 22 to the legs 9 of the U-shaped member 8 oppositely from that illustrated in Figures 1 to 3 inclusive.

Also, if desired, the lower end of the hook 5 may be attached to the inside of the tray 16.

It will be apparent from the foregoing that the parts forming the device may be easily and quickly assembled in position and when separated may be carried or stored in a compact space.

In view of the foregoing description, taken in conjunction with the accompanying drawings, it is believed that a clear understanding of the construction, operation and advantages of the device will be quite apparent to those skilled in the art. A more detailed description thereof is accordingly deemed unnecessary.

It is of course to be understood that the extension ladder arm is changeable to a step ladder arm. As is apparent, the paint pot hook has two arms, one for extension ladders and one for step ladders, inasmuch as extension ladders have round rungs, while step ladders have steps. Consequently one arm will not fit over both types of steps.

Obviously both arms are not used contemporaneously. If used in conjunction with an extension ladder, the rounded hook is connected for use and the step ladder arm is left off and can be carried in an overall pocket, if desired.

It is to be understood, however, that even though I have herein shown and described a preferred embodiment of my invention, the same is susceptible to certain changes fully comprehended by the spirit of the invention as herein described, and the scope of the appended claims.

Having thus described the invention, what I claim is:

1. A paint bucket holder for ladders comprising a hook adapted for attaching to a rung of the ladder, a U-shaped member attached at one side to the lower portion of said hook, said U-shaped member being adapted to straddle a rail of the ladder and having an inner leg adapted to detachably support a tray, a vertically extending bar attached to the other, outer leg of said U-shaped member, a hook at the upper end of said bar adapted for engagement by the bail of a bucket and an arcuate plate at the lower end of said bar adapted to support the side of the bucket.

2. A paint bucket holder for ladders comprising a hook adapted for attaching to a rung of the ladder, a U-shaped member attached at one side to the lower portion of said hook, said U-shaped member being adapted to straddle a rail of the ladder, a vertical bar pivotally attached intermediate its ends to the outer leg of said U-shaped

member, a hook on the upper end of said bar adapted for engagement by the bail of a bucket, and an arcuate plate pivotally attached at the lower end of said bar for engaging the side of the bucket, said bar gravitating into a perpendicular position.

3. A paint bucket holder for ladders comprising a hook adapted for attaching to a rung of the ladder, a U-shaped member attached at one side to the lower portion of said hook, said U-shaped member being adapted to straddle a rail of the ladder and having an inner leg adapted to detachably support a tray, a vertical bar pivotally attached intermediate its ends to the other side of said U-shaped member, a hook on the upper end of said bar adapted for engagement by the bail of a bucket, said bar having an outwardly projecting flange at its lower end and an arcuate plate, adapted to engage a portion of the side wall of the bucket, pivoted at the lower end of said bar and having a notch in its lower edge adapted to receive said flange, said notch being of a length greater than the width of the bar and said bar having pendulous movement to support the bucket in a perpendicular position.

4. A ladder attachment of the class described comprising a hook adapted for attaching to a rung of the ladder, said hook being formed of strap metal and with its lower end twisted to extend flatly against one side of a rail of the ladder, an angularly bent flange at the lower end of said hook, a U-shaped member adapted to straddle the rail of the ladder, the inner side of said U-shaped member resting on said flange, a tray having outwardly extending flanges at its side edges and also formed with a slot in the lower portion of one side thereof, said flange at one side of the tray overlying the inner side of the U-shaped member and said slot being adapted to receive the flange of the hook, means detachably securing said inner side of the U-shaped member and said side of the tray to the lower end of said hook, said tray also having an opening in its body adapted to receive the blade of a putty knife for supporting the knife in an upright position in the tray, and a hanger attached to the other side of said U-shaped member adapted for suspending a bucket therefrom.

WILLIAM CHARLES GEBHARDT.
